ROLLING TYPE CLOSURE CONSTRUCTION
Dominic A. Recchione, Jackson Heights, N.Y., assignor
to Walter Balfour & Co. Inc., Brooklyn, N.Y., a cor-
poration of New York

Filed Feb. 26, 1959, Ser. No. 795,690

2 Claims. (Cl. 160—120)

This invention relates to closures and, more particularly, to rolling doors.

Many new uses have been found for flush mounted type sliding and rolling doors. In some instances, it has been found to be extremely desirable to provide such flush type rolling doors in hotel lobbies, theatres, banks, and the like, whereby it becomes important to the maintenance of the proper decor to provide a neat and finished appearance that will readily blend with the architectural construction of the building. It is therefore an object of the present invention to provide a rolling door installation that is extremely simple in construction, simple to operate, and which provides a completely finished and neat appearance.

Another object of the present invention is to provide a rolling door having guide members that are smooth and free from projections to enable the curtain to slide freely in an even and uninterrupted motion.

A further object of the present invention is to provide guide means for the curtains of rolling doors that will effectively reduce friction, noise, and deformation of the curtain slats, and which will facilitate the opening and closing thereof.

A further object of the present invention is to provide a self-contained locking mechanism within the curtain that is completely hidden from view and which can be manually actuated to retain the curtain in a closed position.

Another object of the present invention is to provide a completely self-contained rolling door installation that can be readily applied between the jambs of a wall opening, or upon the face side thereof, without necessitating any structural changes in the supporting wall or surrounding equipment.

Still another object of the present invention is to provide a rolling curtain type door embodying a removable mullion which will enable such doors to be readily installed in exceptionally long wall openings without excessive strain upon the parts or deformation due to the weight of the curtain that might otherwise result.

An additional object of the present invention is to provide cooperating locking elements that maintain the end posts, mullion, curtain, and storage roll housing in properly connected operating relationship at all times completely independently of the wall within which the door is mounted so as to enable such doors to be readily installed within any wall opening without requiring structural changes in the opening defining portions of the wall.

Still a further object of the present invention is to provide a rolling door unit of the type described that presents a completely uniform and clean exterior appearance, devoid of objectionable fasteners, unsightly irregular portions, and which includes security locking elements that are all completely hidden from view.

Another object of the present invention is to provide a rolling door of the above type that is constructed from a plurality of extruded shapes that slidably interlock with each other to produce the necessary components thereof, thus reducing the number of additional fastening elements required to maintain the parts in proper position and reducing the cost of manufacture of the finished door.

All of the foregoing and still further objects and advantages of this invention will become apparent from a

2

study of the following specification, taken in connection with the accompanying drawing, wherein:

FIGURE 1 is a perspective view of a walled enclosure embodying a rolling door with a removable mullion made in accordance with the present invention;

FIGURE 2 is an enlarged fragmentary perspective view, with parts broken away, showing certain parts of the curtain forming a part of the present invention;

FIGURE 3 is a transverse cross sectional view taken 10 along line 3—3 of FIGURE 2;

FIGURE 4 is an enlarged front elevational view, with parts broken away, of a curtain storage and mounting structure forming another part of the present invention;

FIGURE 5 is an enlarged fragmentary transverse cross 15 sectional view taken along line 5—5 of FIGURE 4;

FIGURE 5a is a view similar to FIGURE 5, showing a slightly modified form of construction;

FIGURE 6 is a fragmentary exploded perspective view 20 of certain parts of an end post channel guide member forming another part of the present invention;

FIGURE 7 is a fragmentary transverse cross sectional view taken along line 7—7 of FIGURE 4;

FIGURE 8 is an exploded perspective view of a hood and mounting plate as used on doors installed under a 25 lintel;

FIGURE 9 is a fragmentary rear perspective view of a removable mullion forming another part of the present invention in operative association with the adjacent door structure;

FIGURE 10 is an enlarged rear elevational view, with parts broken away, of certain parts of the structure shown in FIGURE 9;

FIGURE 11 is a fragmentary longitudinal cross sec- 30 tional view taken along line 11—11 of FIGURE 10;

FIGURE 12 is an enlarged transverse cross sectional view taken along line 12—12 of FIGURE 9;

FIGURE 13 is a fragmentary perspective view of the walled enclosure shown in FIGURE 1, in a completely open position and with the mullion removed;

FIGURE 14 is an enlarged fragmentary longitudinal cross sectional view taken along line 14—14 of FIGURE 2, showing one form of locking mechanism made in accordance with the present invention;

FIGURE 15 is a view similar to FIGURE 3, showing a modified form of locking mechanism;

FIGURE 16 is a fragmentary longitudinal cross sec- 35 tional view taken along line 16—16 of FIGURE 15;

FIGURE 17 is a fragmentary perspective view of a single curtain rolling door made in accordance with the present invention mounted upon the inside face of the opening defining portions of a walled enclosure;

FIGURE 18 is an enlarged fragmentary cross sectional view taken along line 18—18 of FIGURE 17; and

FIGURE 19 is an enlarged fragmentary cross sectional view taken along line 19—19 of FIGURE 17.

Referring now to the drawing, and more particularly to FIGURE 1 thereof, a rolling door installation 20 made in accordance with the present invention is shown in operative association mounted between the jambs defining an opening in one side of a walled enclosure 21. This installation 20 is a multiple curtain unit having a removable mullion, as will hereinafter be more fully explained.

With more specific reference now to FIGURES 2 and 3 of the drawing, a longitudinally flexible and transversely rigid curtain 22 forming a part of the present invention is shown to be constructed from a plurality of preferably extruded aluminum slats 23. One side edge of each slat 23 is provided with a bead 24 that is pivotally received within the female socket 25 formed along the opposite edge of the next adjacent slat. Each bead 24 is slidably received within the adjacent female socket

25 of the next adjacent slat, thus enabling the slats to be assembled without the use of additional fastening elements. However, in order to maintain the slats in proper alignment with each other, end locks 27 are secured, such as by rivets 28, to alternate slats 23, thus blocking the outward movement of the adjacent bead 24 through the end of the closed socket 25.

End posts 30 arranged in accordance with one embodiment of the present invention, are shown more clearly in FIGURES 5 and 6 to be constructed from two extruded shapes, a base part 31 and a guide part 35. The base part 31 defines a longitudinal groove 32 that slidably receives a rail 33 of the guide part 35, so as to enable these two parts to be slidably connected together as a single integral unit. The guide part 35 defines a longitudinal groove 36 into which the adjacent end of the curtain 22 is slidably received. An anti-friction track 37, such as extruded nylon, of substantially trapezoidal cross sectional configuration is slidably received within a similarly shaped groove adjacent to the longitudinal groove 36 of the guide part 35. This track 37 slidably engages the inside surface of the curtain 22 so as to guide it during its longitudinal movement with a minimum amount of frictional resistance. An arcuate guide member 38 also having an anti-friction track element 39 has a depending stem 40 that is received within a socket 42 at one longitudinal end of the guide part 35 of the end post, and secured thereto by means of a screw 41. As is clearly shown in FIGURE 5 of the drawing, mounting bolts 44 are extended through both the guide part 35 and the base part 31 of the end post into securing engagement with expansion bushings 45 disposed in the jamb or wall 43 so as to rigidly secure the end post in place. Since these mounting bolts are on the rear side of the curtain, the front side thereof is completely neat and smooth, completely devoid of any attaching or fastening elements that might otherwise detract from its appearance.

Referring now to FIGURES 4, 7, and 8 of the drawing, a storage unit for receiving the rolling curtain in a storage position is shown to be an integral part of the end posts and associated guide means. End plates 47 are secured, such as by mounting bolts 48 that extend through provided openings 49, to the jamb or wall 43 directly above and in alignment with the base part 31 of the end posts. Each such end plate 47 has a spacer flange 51 that maintains the end plate in properly spaced apart relationship upon the jamb 43. Cylindrical spacers 50 through which the mounting bolts 48 extend further assist in maintaining the end plate 47 in properly spaced relationship with the wall or jamb. Attachment flange 52 in front provides means for securing apron 60 when the door is mounted under a lintel. When the door is mounted on the face of a wall, flange 52 is used to fasten plate 47 to the wall. This hood is shown to include an angular bottom and back plate 59, a top plate 58, and a front apron 60. Angular mounting brackets 61 longitudinally spaced apart throughout the length of the hood provide means for securing the respective plates in proper position relative to each other and the supporting end posts 30. It will be noted that each arcuate guide 38 projects upwardly through the opening 63 between the apron 60 and the facing edge of the bottom plate 59 so as to guide the curtain upwardly therethrough into rolling engagement with a supporting roller 64 of any desired construction. This roller 64, which may include a torsion spring for assisting in the raising and lowering of the curtain, forms no part of the present invention and is thus not illustrated in further detail. Suffice it to state that such roller 64 may be of any desired construction which will enable the curtain 22 to be rollably supported thereon. In all longitudinal movements of the curtains 22, the end posts 30 serve to guide the curtain smoothly and evenly into engagement with the roller. Security lock plates 66, as is more clearly shown in FIGURE 5 of the drawing, extend behind facing shoulders 68 in the

guide part 35 of each end post to prevent canting of the curtain and transverse relative movement thereof. During the installation of the unit, the curtain is assembled with the end posts merely by sliding the curtain into engagement therewith, within the respective channel openings 36.

The removable mullion 70 is more clearly illustrated in FIGURES 9 through 12, and is shown to basically include a pair of end post sections that are secured in back to back relationship with each other by means of nut and bolt assemblies 76. Each such section includes a base part 73 and a guide part 74 that has a frictionless track 75 that functions in a manner similar to that hereinbefore described. The mullion 70 further includes releasable means for locking it in place during the raising and lowering of the curtain, but which permits it to be removed from the window opening when the curtains are in the raised position illustrated in FIGURE 13 of the drawing. Such locking means includes a handle 77 that has a stem 78 projecting into the interior of the base part 73 of each section through a longitudinal slot 79. A block 81 slidably supported within the channel defined by each base part 73 is secured to the opposite end of the handle stem 78 so as to be longitudinally movable therewith throughout the length of the slot 79. A set of spring fingers 82 secured to this block 81 frictionally resist movement of the block 81 between positions. However, longitudinal movement of the block 81 by means of the handle 77 is operative to effect similar longitudinal movement of an inside rod 84 that has a wedge block 85a, b secured to the opposite end. One such wedge block 85a is movable longitudinally into a channel guide 90 upon which an end plate 91 for the curtain storage hood is attached. The other wedge block 85b has a depending pin 86 that is receivable within a well 87 in the counter top 88 of the walled enclosure. Thus, with both handles 77 moved toward their outermost positions, the wedge blocks 85a, b serve to lock the mullion in place within the window opening. By retracting these handles 77, which are accessible only from the interior of the walled enclosure, the mullion can be unlocked so as to be removed after the curtains 22 have been raised to the open position, thus opening the walled enclosure 29a for use. The upper end of each guide part 74 of the mullion is also provided with an arcuate guide member 92 similar to that 38 hereinbefore described for guiding the curtain upwardly into rolling engagement with the supporting roller 64.

Each curtain 22 is further provided with a bottom lock bar 100 that includes an extruded face plate 101 having longitudinal grooves 103 that slidably receive a back plate 105 therewithin. Rivets 106 secure the back plate 105 in properly aligned position with the face plate 101 so as to define a longitudinal housing therewithin. Each side edge of the face plate 101 is provided with a socket 108 for receiving the male bead 24 of the outermost one of the curtain slats 23 on one side, and an astragal 109 on the other side that functions as a seal for snug fit engagement with the counter top 88. Resilient bumpers 111 secured to the inside surface of the bottom lock bar limit the upward movement of the curtain so as to prevent it from moving completely within the hood assembly, so that it is always accessible for movement toward a closed position. Since the bumpers 111 are larger than the opening 63 into the hood, they effectively prevent continued movement of the terminal portion of the curtain therethrough.

A lock assembly made in accordance with one form of the present invention is more clearly illustrated in FIGURES 2, 3, and 14 of the drawing. This assembly includes a housing 115 that is recessed within the rear side of each end of the bottom lock bar 100. A slide bolt 118 is slidably supported within each such housing 115, and has one end of a lock bar 119 secured thereto, such as by a rivet 120. The opposite end of each such

lock bar 119 is slidably supported within a slot 121 within the end plate 122 of the lock bar 100. Thus, in response to sliding movement of the bolt 118, the lock bar 119 can be selectively moved into and out of an aligned opening 124 in the lowermost portion of each end post or mullion, thus locking the bottom bar 100 and the rest of the curtain against longitudinal movement relative thereto. This housing 115 is accessible only from the interior of the enclosure 20, so that it does not detract from the finished appearance on the outside thereof. If desired, a padlock or other retaining means may be extended through aligned openings in the handle part of the sliding bolt 118 and a cross bar 116 of the housing 115 to prevent unauthorized opening of the curtain.

In FIGURES 15 and 16 of the drawing, a slightly modified form of lock assembly 130 is shown to include a single cylinder lock 131 mounted upon the bottom lock bar 100, such as by rivets 132. This cylinder lock 131 includes a shaft 134 to which a cross arm 135 is secured, such as by a key 136. One end of a lock bar 137 is secured, such as by means of a pivot pin 138 to each end of the cross arm 135. Thus, in response to rotation of the cylinder lock 131, the lock bars 137 are simultaneously moved inwardly and outwardly through aligned slots 140 in the end plates 139 at the opposite ends of the bottom bar 100, into and out of engagement with similarly aligned slots 142 in the end posts and mullion. In this embodiment, a single rotation of the cylinder lock 131 is operative to lock and unlock both sides of the bottom lock bar 100.

As shown in FIGURE 5a, a substantially wider base post 31a is used in connection with the channel guide post 35 with doors operated by crank where greater clearance is required on one side to provide necessary space for the operating device. During such installation, a substantially longer mounting bolt 44a is required to secure the assembled post 30a to the wall or jamb 43.

With reference now to FIGURES 17 to 19, an installation 150 is shown that is mounted upon the inside face of a wall 152 that defines an opening 151 through which access is to be controlled. In this embodiment, the mounting bolts 153 extend through aligned openings 154 in both the base part and guide part of the end posts so that the curtain overlaps the openings defining portions on the inside of the wall. In this arrangement, auxiliary mounting holes 49a in the flange 52 of the hood end plates are used to mount the hood upon the wall completely hidden from view. The universal and symmetrical construction of the related parts enables this rolling door to be equally as well installed between the jambs or upon the face of the wall, to suit any desired purpose.

While this invention has been described with particular reference to the construction shown in the drawing, it is to be understood that such is not to be construed as imparting limitations upon the invention, which is best defined by the claims appended hereto.

Having thus described my invention, I claim as new and desire to secure by Letters Patent:

1. A self contained rolling type closure assembly comprising, in combination, a pair of spaced apart parallel guide members, a curtain slidably supported by said guide members for reciprocating longitudinal movement between a retracted open position and an extended closed position, said curtain comprising a plurality of substantially identical rigid slats, each of said guide members comprising a channel member having a longitudinal shoulder facing outwardly in a direction away from said curtain, connection means pivotally securing each side edge of each said slat to an adjacent side edge of the next adjacent slat whereby said curtain is flexible in a longitudinal direction parallel to said guide members and rigid in a direction extending transversely between said guide

members, security lock means carried by said curtain and slidably engaged by said guide members maintaining said slats transversely within and normal to said guide members and securing the ends of said slats within said guide members against displacement out of said guide members, said security lock means comprising a plurality of angle brackets secured to the adjacent lateral edge of said curtain overlying and locking behind said shoulders, each of said brackets adapted to overlap the edge of an adjacent slat, roller means at one longitudinal end of said guide members rollably supporting said curtain in said open retracted position, and latch means at the opposite longitudinal end of said guide members releasably securing said curtain in said extended closed position.

2. A self contained rolling type closure comprising, in combination, a pair of spaced apart parallel guide members, a continuous curtain slidably supported by said guide members for reciprocating longitudinal movement between a retracted open position and an extended closed position, said curtain being flexible in a longitudinal direction parallel to said guide members and being rigid in a transverse direction intermediate said guide members, roller means at one longitudinal end of said guide members rollably supporting said curtain in said retracted open position, each one of said pair of guide members comprising a substantially rigid channel member opening inwardly toward said curtain and slidably receiving one lateral edge of said curtain therewithin, an anti-friction track element integral with each one of said guide members projecting into said channel and defining an anti-friction surface slidably engaging one facing side of said curtain, and removable arcuate guide members each co-extensive at one extremity with said one longitudinal end of its associated guide member, the opposite extremity of said arcuate guide member extending freely toward said roller means and defining a removable extension of said track element beyond said guide member in a direction toward said roller means, said curtain including an inside hidden surface and an outside exposed surface, said track slidably engaging said inside surface, said arcuate guide extending longitudinally and outwardly away from said inside surface toward said roller means, said curtain comprising a plurality of substantially identical rigid slats, each one of said slats extending transversely between said guide members, connection means pivotally securing each side edge of each slat to an adjacent side edge of the next adjacent slat, security lock means securing the opposite ends of said curtain transversely within said guide members against displacement out of said channels, each said channel member including a longitudinal shoulder facing outwardly in a direction away from said curtain, said security lock means comprising a plurality of brackets secured to the adjacent lateral edge of said curtain overlying said shoulder.
